2 Sheets—Sheet 2.

UNITED STATES PATENT OFFICE.

ANDREW L. REINER, OF BLUE ISLAND, ILLINOIS, ASSIGNOR TO THE EXPORT IMPLEMENT MANUFACTURING COMPANY, OF SAME PLACE.

SICKLE-GRINDER.

SPECIFICATION forming part of Letters Patent No. 637,946, dated November 28, 1899.

Application filed June 12, 1899. Serial No. 720,154. (No model.)

To all whom it may concern:

Be it known that I, ANDREW L. REINER, a citizen of the United States, residing at Blue Island, in the county of Cook and State of Illinois, have invented a new and useful Improvement in Sickle-Grinders, of which the following is a specification.

This invention relates to sickle-grinders.

The object of the invention is to provide a machine of simple and economical construction and arrangement and easily operated for sharpening sickles, saws, cutters, and the like.

The invention consists, substantially, in the construction, combination, location, and arrangement of parts, all as will be more fully hereinafter set forth, as shown in the accompanying drawings and finally specifically pointed out in the appended claims.

Referring to the accompanying drawings and to the various views and reference-signs appearing thereon, Figure 1 is a view in side elevation of a machine constructed in accordance with the invention. Fig. 2 is a broken detail view in side elevation, showing the operation of the means for vibrating the grinder-supporting bracket. Fig. 3 is a plan view of the machine. Fig. 4 is a similar view to Fig. 2, illustrating the operation of the apparatus. Fig. 5 is a broken detail view in section, showing the construction for detachably securing the grinder-supporting bracket to the cam-lever. Fig. 6 is a similar view showing the grinder-supporting bracket secured against swing.

The same part is designated by the same reference-sign wherever it occurs throughout the several views.

Reference-sign A designates a supporting-base of the machine and, if desired, may be in the form of a casting having formed therewith or carried or otherwise secured thereto a standard B. Mounted on said standard is a casting C, said casting being mounted for vertical adjustment in any suitable manner—as, for instance, by the set-screw D, through which said casting is rigidly held when adjusted to the required height. In a hub E, formed on or secured to casting C, is mounted a pin or stud F. The casting C is provided with an extension G, in which is journaled a

pin or stud H, carrying on one end a fly-wheel J and on the other a pinion K. Reference-sign L designates a casting having the arms M N sleeved at one end upon the stud or pin F, and a shaft O is mounted in the other end of said arms, said shaft carrying the grinder-wheel P and also a pinion Q. Suitably journaled upon stud or pin F is a main drive or operating gear R, arranged to mesh at substantially diametrically opposite points with the pinions K and Q, whereby when said drive or operating gear is rotated rotation is imparted simultaneously to the shafts H and O, thereby imparting rotation to the fly-wheel J and to the grinder P, the fly-wheel serving not only as a counterbalance, but also to steady the operation of the apparatus.

The arm N of bracket L is provided with an extension S beyond the pin or stud F, which extension is slotted, as indicated at T, and a co-operating curved slot A' is formed in casting C. A headed bolt or other securing device B' is arranged to pass through the slots T A' to secure or connect the extension S of arm N to the casting C.

Suitably journaled at one end upon the shaft H is a lever C², said lever carrying a fork or yoke D² at its other or free end. Suitably mounted on or carried with the hub of main drive or operating gear R is a cam E', arranged to operate in the yoke or fork D². When suitably adjusted, the head F² of bolt B' is adapted to engage a shoulder or seat in lever C², as clearly shown in Figs. 3, 4, and 5, the slot T enabling said bolt to be detached from engagement with said seat, as clearly shown in Figs. 2 and 6.

The operation of the apparatus as above described, when the securing-bolt B' is adjusted into position for engagement with the lever C², is as follows: When rotation is imparted to the main drive or operating gear R, simultaneous rotation is transmitted through the engagement of said gear with pinions K and Q to the balance or fly wheel J and to the grinder B. Rotation is also imparted to the cam E', which, operating within the fork or yoke D², imparts an oscillation to lever C², and by reason of the engagement of locking-pin D' with said lever C² an oscillatory movement or vibration is imparted to

bracket L, said bracket oscillating or swinging upon the pin or stud F, thus raising and lowering the grinder P. Thus I secure the effect of a compound lever in effecting the vibration or oscillation of bracket L, with the accompanying advantages of smoothness and easiness of operation, the curved slot A' in casting C permitting the vibratory swing of bolt B' with reference to said casting. When 5 it is desired to operate the grinder in stationary position—that is, without vibration of its supporting-bracket—the securing-bolt B' is detached from engagement with the lever C² and is moved laterally in slots T and A' until such disengagement is effected and said 10 bolt occupies the position shown in Figs. 2 and 6, when by tightening up the nut G² on said bolt the arm N of bracket L is clamped to casting C, thereby holding and maintaining 15 the bracket L, which carries the grinder, in rigid relation with respect to said casting. Thereafter the actuation of main drive-gear R will impart a rotation to the grinder in the manner above described, but the bracket L, 20 carrying the grinder, being detached from the lever C² no vibration will be imparted to the grinder-supporting bracket, the lever C² merely vibrating about its journal-support on pin H without imparting a vibration to the 25 bracket L.

If desired, a spring H² may be arranged to oppose the swing or movement of bracket L in a direction to advance or move the grinder toward its work during the vibration of said 30 bracket, said spring operating to assist in elevating said bracket upon the return movement thereof.

Many changes and variations in the details of construction and arrangement would 35 readily suggest themselves to persons skilled in the art and still fall within the spirit and scope of the invention. I do not desire, therefore, to be limited or restricted to the exact details of construction and arrangement shown and described, but,

Having now set forth the object and nature of my invention and a construction embodying the principles thereof, what I claim as new and useful and of my own invention, 45 and desire to secure by Letters Patent of the United States, is—

1. In an apparatus of the class described, a frame, a stud mounted therein, a bracket sleeved upon said stud and carrying a grinder, 50 said bracket provided with an extension beyond said stud, a drive-gear journaled upon said stud, a cam connected with said drive-gear, a rock-lever arranged to be vibrated by said cam, and means for connecting said extension to said lever, as and for the purpose set forth.

2. In an apparatus of the class described,

a frame provided with a slot, a stud journaled in said frame, a bracket sleeved upon said stud and provided with a slotted extension, a grinder mounted in said bracket, a drive-gear journaled upon said stud and carrying a cam, a rock-lever arranged to be engaged and vibrated by said cam, and a securing-bolt mounted in the slots in said frame and bracket for detachable engagement with said lever, as and for the purpose set forth. 65

3. In an apparatus of the class described, a frame comprising a base having a standard, a casting mounted on said standard, a pin or stud mounted in said casting, a bracket sleeved upon said stud and projecting on one side thereof, a shaft journaled in the free end of said bracket and carrying a pinion and a grinder, said casting provided with an extension on the opposite side of said stud, a shaft mounted in said extension and carrying a pinion and a fly-wheel, a drive-gear journaled upon said stud and engaging said pinions, and means for connecting said bracket to said casting, as and for the purpose set forth. 75

4. In an apparatus of the class described, a frame comprising a base-plate and a standard, a casting mounted on said standard and carrying a stud or pin, a bracket sleeved upon said stud or pin and projecting on one side thereof, a shaft mounted in the free end of said bracket and carrying a pinion and a grinder, said casting provided with an extension projecting on the opposite side of said stud or pin, a shaft journaled in said extension and carrying a pinion and a fly-wheel, a drive-gear journaled upon said stud or pin and arranged to engage said pinions, a pivotally-mounted lever, a cam carried by said drive-gear and arranged to engage and vibrate said lever, and means for detachably connecting said bracket and lever, as and for the purpose set forth. 90

5. In an apparatus of the class described, a frame, including a casting, a pin or stud mounted therein, a bracket sleeved upon said stud and carrying a grinder, a drive-gear journaled upon said pin or stud and carrying a cam, a lever pivotally mounted upon said casting and carrying a yoke arranged to receive said cam, whereby said lever is vibrated, said bracket provided with an extension, and means for detachably engaging said extension and lever, as and for the purpose set forth. 95

In witness whereof I have hereunto set my hand, this 9th day of June, 1899, in the presence of the subscribing witnesses.

ANDREW L. REINER.
